CONDENSER BUSHING

Thomas F. Brandt, Barberton, Ohio, and Robert H. Hose,
Mountainside, and Thomas Brendgord, Englewood,
N. J.

Application June 12, 1956, Serial No. 41,882

Term of patent 14 years

(Cl. D26—10)

FIG. 1

FIG. 2

FIG. 3

Fig. 1 is an elevation view of the condenser bushing showing our new design;

Fig. 2 is a top plan view of the bushing; and
Fig. 3 is a bottom plan view of the bushing.

We claim:

The ornamental design for a condenser bushing, as shown.
